Inventor:
Alvarado L.R. Ellis,

by *Alvarado L.R. Ellis*
His Attorney.

UNITED STATES PATENT OFFICE.

ALVARADO L. R. ELLIS, OF SWAMPSCOTT, MASSACHUSETTS, ASSIGNOR TO GENERAL ELECTRIC COMPANY, A CORPORATION OF NEW YORK.

PIEZO-ELECTRIC DEVICE.

Application filed July 14, 1925. Serial No. 43,630.

My invention relates to devices comprising a piezo-electric member interposed between a pair of electrodes, and has for its principal object the provision of an arrangement wherein the undesirable effects of the electrodes on the free vibration period of the piezo-electric member are avoided or greatly reduced.

The free vibration period of a piezo-electric oscillator, such as a slab or disk of quartz for example, is determined for the most part by the dimensions of the slab but is affected to some extent by its mounting and by variation in the conditions under which it is operated. If it were possible to suspend a piezo-electric oscillator in the air so that it could be made to oscillate freely, a layer of air adjacent its vibrating surfaces would oscillate just as though it formed an integral part of the piezo-electric member. It is of course necessary that the oscillator be provided with some sort of a mounting and it is desirable that it be protected from dust and moisture by a suitable casing. The mounting and casing, however, are likely to prevent free movement of the oscillator surfaces and the layer of air associated therewith and to produce variation in the resonance frequency of the oscillator. In accordance with my invention, this difficulty is largely avoided by the provision of electrodes formed and mounted in a manner to permit ready movement of the oscillator surfaces and the layer of air adjacent thereto.

My invention will be better understood from the following description when considered in connection with the accompanying drawing and its scope will be pointed out in the appended claims.

Referring to the drawings, Fig. 1 shows a piezo-electric device wherein my invention has been embodied; and Fig. 2 shows a modification thereof.

Fig. 1 shows a piezo-electric member 1 supported upon an electrode 2 which is mounted on an insulation base 3 and is connected to a terminal 4 through means shown as a screw

5. An electrode 6 located adjacent the upper surface of the member 1 is spaced from the base 3 by a conductive ring 7 and is connected to a terminal 8 through means shown as a screw 9, the electrode 6 and ring 7 be-

ing shown as cut away to expose the piezo-electric member 1 and electrode 2 which are 55 located in the chamber formed by base 3, electrode 6 and ring 7. In order to simplify the drawing, the electrode 6 has been shown as located at some distance from the oscillator 1. It should be understood however that 60 in an actual construction the spacing between the oscillator 1 and electrode 2 is but a few thousandths of an inch.

In order to permit ready movement of the air adjacent the upper surface of the oscillator 1, the lower surface of the electrode 6 is slotted transversely and longitudinally or otherwise constructed to form small areas spaced apart to reduce the friction incident to movement of the air between it and the 70 surface of the oscillator. With these small areas the air moved due to change in the thickness of the oscillator has to traverse the thin air gap between electrode 6 and oscillator 1 only a short distance before it 75 encounters one of the slots; the in and out flow of the air produced by vibration of the oscillator surfaces is greatly facilitated; and the effect of the mounting on the resonance 80 frequency of the oscillator is correspondingly reduced.

Fig. 2 shows an embodiment of the invention wherein the oscillator 1 is interposed between electrodes 10 and 11 which are made of perforated metal, wire gauze, or 85 the like. This construction like that of the arrangement of Fig. 1 has the advantage that the electrodes may be placed very close to the oscillator without interfering to any considerable extent with the movement of 90 air adjacent its surfaces.

The embodiments of the invention illustrated and described herein have been selected for the purpose of clearly setting forth the principles involved. It will be apparent, however, that the invention is susceptible of being further modified to meet the different conditions encountered in its use and I therefore aim to cover by the 100 appended claims all modifications within the true spirit and scope of my invention.

What I claim as new and desire to secure by Letters Patent of the United States, is:

1. The combination of a piezo-electric oscillator, and an electrode having a plurality 105 of surface areas located adjacent a surface of

said oscillator whereby the friction incident to the movement of air between the surfaces of said oscillator and said electrode is reduced.

5. 2. The combination of a piezo-electric oscillator, and electrodes mounted adjacent opposite surfaces of said oscillator and provided with a plurality of surface areas whereby the effect of said electrodes on the

free vibrating period of said oscillator is reduced.

3. The combination of a pair of electrodes formed of wire gauze, and a piezo-electric oscillator interposed between said electrodes.

In witness whereof, I have hereunto set my hand this 10th day of July, 1925.

ALVARADO L. R. ELLIS.
